Filed Aug. 2, 1971, Ser. No. 168,523

Term of patent 14 years

Int. Cl. D7—99

U.S. Cl. D55—1 J

FIG. 1 is a three-quarter front top perspective view of the food warmer showing my new design.

FIG. 2 is a rear elevational view thereof.

The sides not illustrated correspond in form to those shown.

The characteristic feature of my design for the food warmer shown resides in the specific appearance and configuration of the rod-like supports as shown.

I claim:

The ornamental design for a food warmer, as shown and described.
